BODY ROLLER

Edward Charles Kradoska, Melrose, Pa.

Application April 13, 1949, Serial No. 87,273

8 Claims. (Cl. 153—54)

1

My invention relates to a body roller of the type used for removing dents and bumps from the chine, body bulges and bead of open head steel drums.

One object of the invention is to produce an improved machine of the type set forth.

A further object is to produce an improved machine whereby dents and bumps may be removed from the body of the drum as well as from the chine, body bulges and bead thereof, and regardless of whether the bung hole is in an end wall or in the side of the drum.

A still further object is to produce an improved machine which will be efficient and easy to operate.

These and other objects are attained by my invention as set forth in the following specification and as illustrated in the accompanying drawings in which:

Fig. 1 is a side elevational view of a machine embodying my invention.

Fig. 2 is a vertical sectional view of the same.

Fig. 3 is a rear, or left hand, end elevational view of the same.

Fig. 4 is a view, partly in vertical section and partly in front, or right-hand, elevation of the same.

Figs. 5, 6 and 7 are elevational views showing certain details of construction.

Fig. 8 is a diagrammatic and fragmentary elevational view showing one position of a stop forming part of the machine.

Fig. 9 is similar to Fig. 8 except that it shows another position of the stop.

Fig. 10 is an enlarged, fragmentary sectional view of the front, or right-hand, end of the machine as shown in Figs. 1 and 2.

Figs. 11 and 12 are fragmentary views showing the manner in which the machine can be used for smoothing the body, as distinguished from the chine of a drum.

Fig. 13 is a fragmentary, sectional view showing the manner in which the chine at the closed end of the drum is smoothed.

The machine illustrated includes a suitable frame to which is suitably secured an elongated, horizontally disposed housing 10 which carries a roller 12 for supporting the drum to be repaired. The roller 12 is rotated about its longitudinal axis by means of a gear 14 which meshes with a pinion 16 driven by a motor M.

The roller 12 is provided with a relatively wide cylindrical surface 18 and on its outer, or right hand, vertical face it is provided with projecting lugs which have tapped openings 22 for receiv-

2

ing bolts 24 which are carried by, and which pass through an outer roller 26, whereby the roller 26 is supported by the roller 12 as best shown in Figs. 2 and 10. The end roller 26, which is shown in Fig. 7, is of the same diameter as, and its surface forms an extension of the surface of the roller 12 and hence, the surface of the roller 26 has also been designated by reference numeral 18. In other words, the head 12 and the end roller 26 co-act to provide a cylindrical support for the drum 28, portions of which are shown in section in Figs. 9, 11, 12 and 13 and in broken lines in Fig. 10.

Mounted between the roller 12 and the end roller 26, is a forming plate 30 which is best shown in Fig. 6. The plate 30 is provided with openings 32 through which the lugs 20 pass and the periphery 34 of this plate is shaped according to the effect to be produced. In Fig. 15 it is shown as it would be shaped when it is to be used in removing dents from the body bulges of a steel drum and, therefore, the contour of the periphery 34 of the plate 30, as seen from its cross section in Figs. 2 and 10, is such as to conform to the shape of the cross section of the bulge. It is to be understood, however, that the contour of the rim of the plate 30 may be changed as may be desired. The openings 32 in the plate 30 are much bigger, in all directions, than the lugs 20 which pass therethrough so as to permit the plate 30 to move, radially, relative to the rollers 12 and 26 such for example as from the position of Fig. 2 to the position of Fig. 10.

The plate 30 is also provided with a central opening 36 through which extends a shaft 38. The shaft 38 is provided with a head formed of a reduced inner cylindrical portion 40, an intermediate conical portion 42, and an enlarged outer cylindrical portion 44. It will be noted that the conical portion is adapted to pass freely through the opening 36, but that the outer cylindrical portion 44 is adapted to fit snugly in the opening 36. Therefore, when the shaft 38 is moved to the right, or to the position of Fig. 2, the plate 30 is supported by the reduced cylindrical portion 40 and the plate 30 drops to the position of Fig. 2 in which its upper periphery is flush with, or below, the adjacent surfaces of the roller 12 and the roller 26. When the shaft 38 is moved to the left until the outer cylindrical portion 44 seats in the opening 36, the plate 30 becomes concentric with the rollers 12 and 26 and, the diameter of the plate 30 being greater than that of the rollers 12 and 26, the

periphery 34 of the plate 30 will project, uniformly, beyond the cylindrical surfaces 18 of the rollers 12 and 26. The intermediate conical portion 42 guides or facilitates the entry of the outer cylindrical portion 44 into the opening 36.

The shaft 38 may be moved by any suitable means, but, according to my invention, I provide a double-acting air cylinder 46 adapted to move a plunger 48 to the right or to the left, as viewed in Fig. 2, and I connect the plunger 48 to the shaft 38 by means of a universal joint 50. The air cylinder 46 is connected to a double acting valve 52 by means of pipes 54 and the valve is supplied with air through a pipe 56 leading from a suitable source not shown. The pressure of the air is indicated by a gauge 58 cut into the supply line in the usual manner. The air valve is operated by means of a lever 60 so as to supply air to one side or the other of the air cylinder to move the plate 30, through the instrumentality of the shaft 38 to the position of Fig. 2 or, to the position of Fig. 10.

Co-acting with the lower rollers 12 and 26 are two rollers 62 and 64 each of which is provided with an inner end groove 66 for operating on the bead at the open end of a drum, and with an intermediate groove 68 for operating on the body bulges of the drum. The rollers 62 and 64 are mounted on stub shafts 70 and 72 which are journaled in opposite walls of a yoke 74. Either or both of the rollers 62 and 64 may rotate freely or may be positively driven but in my improved machine I provide means for driving only one of these rollers. As will be seen from Figs. 2 and 10, the roller 64 is keyed, at 80, to its stub shaft 72 which is connected by means of a universal joint 76 to a shaft 78, which is driven by means of pinion 82 meshing with the gear 14, which drives the lower rollers 12 and 26, all as shown in Fig. 2.

The rolls 62 and 64 are adapted to be moved, vertically, relative to the lower rollers 12 and 26, or from the position of Fig. 2 to that of Fig. 10, by means of a single acting air cylinder 90 which, when supplied with air under pressure, serves to depress the sleeve 92 which carries the yoke 74 which carries the rollers 62 and 64. The air cylinder 90, which is available on the market and is therefore not described in detail, is controlled by a foot operated valve 96 to which it is connected by pipes 98 which are supplied by air from supply pipe 56. The valve 96 is such that, in one position thereof, it admits air into the air cylinder 90 and in another position thereof it exhausts air from this air cylinder. The air cylinder 90 and the sleeve 92, and, hence, the rollers 62 and 64 are normally maintained in the upper position of Figs. 1 and 2, by a spring 100 which is confined between a fixed block 102 and the top wall of the sleeve 92. The fixed block 102 is carried by a cross bar 103 which is mounted on the frame of the machine and which projects into the sleeve 92 through opposite vertical slots 104 formed in the wall of the sleeve, to permit vertical movement of the sleeve relative to the fixed block.

In order to support the drum while it is being operated on, I provide a cradle which is best shown in Figs. 2 and 11. This cradle includes a pair of arms 106, which carry rolls 108 and is pivoted at 110 to a support 112, which is secured to the bottom frame of the machine as at 114. The pivot of the cradle is such that it can tilt or rock, in a longitudinal direction, between the positions of Figs. 1 and 2, and so that it also has a limited play in a transverse direction, or in a

direction at a right angle to the direction of tilting shown in Figs. 1 and 2. By this means the cradle provides a "flexible" or self-adjusting support for the drum.

The machine illustrated also includes a stop for positioning the bead of an open end drum. This stop is best shown in Figs. 8, 9 and 10 and includes a shoe 118 carried by an arm 120 which is pivoted at 122 to the frame of the machine so that the shoe may be raised from, or lowered into contact with the surface 18 of the rollers 12 and 26. The arm 120, and, hence, the shoe 118, are biased upwardly, or to the position of Fig. 9, by a spring 124 and are adapted to be moved to the lower position of Fig. 8, in which the shoe rests on the roller 12, by means of a conventional over-center toggle such as that shown in Figs. 8, 9 and 10.

The toggle mechanism, which need not be described in detail, is actuated by means of a lever 126 having a handle bar 128 and the arrangement is such that, when the lever 126 is moved downwardly or to the position of Figs. 8 and 10, the shoe 118 will move to its lower position in which it rests on the roller 12 and in which its outer end underlies the inner ends of the upper rolls 62 or 64. In this position, the shoe 118 forms a stop so that when the end of the drum abuts it, the bead 130 of the drum will register with the inner grooves 66 on the upper rolls 62 and 64. When the lever 126 is moved to the upper position of Fig. 9, the toggle is collapsed and the spring 124 raises the arm 120 and the shoe 118 so as to permit the drum to be moved inwardly between the lower and upper rollers until the bulge or bulges 132 of the drum come into registration with the periphery 34 of the plate 30 and the grooves 68 of the roller 62 and 64.

The outermost roller 26 is provided with a central recess 134 for accommodating the end of the shaft 38, when the latter is in the position of Fig. 2, and is also provided with counter-bore or recess 136 in the outer face thereof. A cover plate 138 seats in the recess 136 and is secured in position by a bolt or the like 140.

The operation is as follows: When the bead 130 at the open end of the drum is to be rolled, to eliminate dents and bumps, the lever 126 is moved to its lower position so as to bring the shoe 118 to its lower effective position as shown in Figs. 8 and 10. The drum is now placed on the rolls 108 of the supporting cradle and it is moved inwardly between the upper and lower rollers until its bead abuts the end of the shoe 118. The foot valve 96 is then operated to lower the yoke 74 and the rollers 62 and 64 into the effective position of Fig. 10 in which the inner grooves 66 of the rollers 62 and 64 will be in registration with the bead of the drum. The switch 142 is now closed to energize the motor M and rotate the lower rollers 12 and 26 and the upper roll 64. The switch 142 is double acting and the motor M is of the reversing type so that, when the switch 142 is moved to one position, the motor shaft will turn in one direction and, when the switch is moved to another position, the motor shaft will turn in the opposite direction.

When it is desired to smooth out a bulge formed in the body of the drum, the lever 126 is moved to the upper position of Fig. 9 so as to allow the spring 124 to raise the shoe 118, and permit insertion of the open end of the drum inwardly past the inner ends of the rollers 62 and 64. The valve 52 is then operated so as to move the shaft

38 to the left and bring the plate 30 to its effective position, which is shown in Fig. 10. Now, with the shoe 118 and rollers 62 and 64 in their upper positions, the drum is moved inwardly over the lower rollers until the bulge to be smoothed out registers with the periphery 34 of the plate 30 and the grooves 68 of the rollers 62 and 64. The upper rollers are now lowered by manipulation of the foot valve 96 and the switch 142 is closed to energize the motor M. In some instances, the bead of the drum and the adjacent body bulge are so spaced that they can be smoothed out in one operation as shown in Fig. 10.

When the chine 144 of the side wall of the drum adjacent its bottom 146 is to be smoothed out, it is only necessary to energize the motor to place the chine 144 over the outer end of the roller 26 and to lower the rollers 62 and 64 as diagrammatically shown in Fig. 13.

As will be seen from Fig. 10, when a body bulge is being rolled, the adjacent portions of the drum body will also be rolled. In many, if not most, cases, the width of the rollers 62 and 64 is such that one-half of the area between two body bulges is rolled with the rolling of one bulge and the rest of the area is rolled when the second bulge is rolled. When a side-filled drum is to be rolled, the bung hole and the fitting 148 thereon will be in the way and a band of a width equal to, or slightly greater than, the diameter of the fitting 148 would ordinarily remain unsmoothed. But, according to my invention, this band or area can be smoothed in the manner shown in Figs. 11 and 12. As shown in these figures the drum is adjusted until the bung hole fitting 148 registers with the rollers 62 and 64. The upper and lower rollers are rotated in one direction until they are about to abut one side of the fitting 148 and are then rotated in the reverse direction until they are about to abut the opposite side of the fitting, as shown in Figs. 11 and 12. It will be understood that, except when rolling one of the body bulges the plate 30 is always in the lower, ineffective position of Fig. 2.

What I claim is:

1. A machine for removing dents and bumps from a metallic drum, or from a bead, or a bulge on such drum, said machine including a first cylindrical roller, a second cylindrical roller, a reversible motor for rotating said rollers about parallel axes, one of said rollers being movable towards, or away from the other of said rollers, there being a bead-engaging groove near one end of said second roller, and a bulge-engaging groove in said second roller intermediate the ends thereof, said groove and the cylindrical body of said second roller being arranged to engage said bead, said bulge and the body of said metallic drum, respectively, means for moving said movable roll roller into operative position relative to the other of said rollers, and a switch for controlling the direction of rotation of the motor.

2. The structure recited in claim 1 in which said first roller is disposed below said second roller and in which said second roller is movable towards, and away from, said first roller.

3. The structure recited in claim 1 together with a movable stop, means for moving said stop to a first position in which it obstructs the space between said rollers and limits the extent to which the body wall may be inserted between said rollers to align the bead at the end of said body with said bead engaging groove, and to a second position in which said stop does not obstruct said space.

4. A machine for removing dents and bumps from the beads, bulges, or body portions of a metallic drum, said machine including a lower, rotatable, but otherwise immovable roller, an upper, rotatable and vertically movable roller, a motor for rotating said rollers about parallel axes, means for raising said upper roller for insertion of a wall of the drum between said rollers, means for lowering said upper roller whereby said upper and lower rollers engage the outer and inner surfaces, respectively, of a drum inserted therebetween, and a pivotally mounted cradle disposed near said rollers for movably supporting the drum while the latter is in engagement with said rollers.

5. A machine for removing dents and bumps from the bead, the chine and the body of a metallic drum, said machine including a lower, rotatable, but otherwise immovable roller, an upper, rotatable, but vertically movable roller, means for rotating said rollers, means for moving said upper roller to a lower position in which said rollers engage the inner and outer surfaces, respectively, of the wall of a drum inserted therebetween, there being a bulge engaging groove in said upper roller, lugs carried by said lower roller, a forming plate of a diameter larger than that of the lower roller and having apertures therein through which said lugs pass, said apertures being much larger than said lugs and the contour of the periphery of said plate being complementary to the contour of said bulge-engaging groove, said plate also having a central opening therein, a shaft extending through said central opening and having a reduced portion which fits loosely in said central opening and an enlarged portion which fits snugly in said central opening, and means for moving said shaft to a first position in which the reduced portion of the shaft engages said central opening and said plate is eccentric to said lower roller and its upper periphery is disposed below the adjacent periphery of the lower roller, and to a second position in which the enlarged portion of the shaft engages said central opening and said plate is concentric with the lower roller and its periphery projects beyond the periphery of the lower roller.

6. A machine of the type disclosed including a first roller and a second roller, means for driving at least one of said rollers, means for moving one of said rollers towards, and away from, the other of said rollers, there being a slot formed in said first roller, a forming disc having a diameter larger than the diameter of said first roller, means loosely mounting said disc in said slot whereby said disc is movable to a first position in which it is eccentric to said first roller and a portion of the disc is disposed inwardly of the periphery of the first roller and the opposite portion of the disc projects beyond the periphery of said first roller, and to a second position in which the disc is concentric with said first roller and the entire periphery of the disc projects beyond the entire periphery of said first roller, and means for moving said disc to said second position and for retaining it in said second position.

7. The structure recited in claim 6 in which said first roller is below said second roller and said disc is movable to its first position by gravity.

8. A machine for removing dents and bumps from a metallic drum, or from a bead, or a bulge on such drum, said machine including a first cylindrical roller, a second cylindrical roller, a reversible motor for rotating said rollers about parallel axes, one of said rollers being movable

towards, or away from, the other of said rollers, there being a bead-engaging groove near one end of said second roller and a bulge-engaging groove in said second roller intermediate the ends thereof, said grooves and the cylindrical body of said second roller being arranged to engage said bead, said bulge and the body of said drum, respectively, means for moving said movable roller into operative position relative to the other of said rollers, there being a recess formed in the periphery of said first roller, a forming member movably mounted in said recess, said forming member normally occupying a first position in which its periphery does not project beyond the surface portion of said first roller which is adjacent said second roller, and means operable at

will for moving said forming member to, and retaining it in, a second position in which its periphery projects beyond said surface portion.

EDWARD CHARLES KRADOSKA.
